UNITED STATES PATENT OFFICE.

CHARLES A. CREAPO, OF ST. PAUL, MINNESOTA.

GRAIN-CAR DOOR.

1,159,651.

Specification of Letters Patent.

Patented Nov. 9, 1915.

Application filed February 2, 1914. Serial No. 815,950.

To all whom it may concern:

Be it known that I, CHARLES A. CREAPO, a citizen of the United States, residing at St. Paul, in the county of Ramsey and State 5 of Minnesota, have invented a new and useful Improvement in Grain-Car Doors, of which the following is a specification.

The object of this invention is the production of a fire proof door for use upon 10 grain cars which can be easily and quickly attached to or detached from the door frame of an ordinary freight car. Doors for grain cars heretofore provided have usually been too complicated and expensive when 15 of sufficient strength to be commercially practicable. My invention produces a strong and extremely simple structure composed of sections of corrugated metal and channel members which may be easily and 20 quickly adjusted to the sides of a doorway, making the invention feasible for temporary use during the busy season of shipping grain and permitting it to be entirely removed 25 from the car quickly when the car is used for transporting other freight.

In the accompanying drawing forming part of this specification, Figure 1 is a section of a fragment of a car having my novel door applied thereto, said section being 30 taken upon the line X—X of Fig. 2; Fig. 2 is another section of a fragment taken in a horizontal plane through the car body such as on the line Y—Y of Fig. 1; Fig. 3 is a perspective of a detail of one of the parts of 35 the door; Figs. 4 and 5 are side views partly broken away and in section of one of the channel members in which the door sections are adapted to be held, and Fig. 6 is a section of a detail.

40 In the drawing A indicates a fragment of an ordinary freight car having the usual door way B. The bottom of this doorway is formed by the floor 2 of the car in the ordinary manner and the sides by the vertical uprights 3 and 4, (see Fig. 2). The ordinary door 5 is also indicated on the outside of the car, this door being adapted to be closed and sealed in the usual manner after the car has been filled with grain and my 45 improved door C being employed inside.

50 My improved grain car door consists of a series of superimposed horizontal sections 6 which are similar in construction. Each of these sections consists of a piece of corrugated metal, the corrugations of which ex-

tend longitudinally and horizontally when the sections are placed in the doorway. Each end of each section is incased in a strip of channel iron 7, (see Fig. 3), which is secured to the corrugated metal such as 60 by rivets 8. This channel member reinforces the strength of the corrugated section, preventing it from bending or expanding across the corrugations and also forms a pocket which prevents any grain leaking out of the 65 door around the ends of the sections. Secured to each of the uprights 3 and 4 is a vertical I beam 9 which is placed with one of its bars 10 resting flat against the inner surface of the upright. The lower end of 70 this I beam is formed with projecting teeth 11 which are adapted to engage in the surface of the floor to hold the lower end of the beam in position laterally and longitudinally of the car. The upper end of the 75 I beam has formed upon the bar 10, a pair of bosses 12 and 13 which are adapted to straddle the upright to hold the upper end of the I beam longitudinally of the car. For the purpose of holding the I beam laterally 80 and vertically of the car, inwardly projecting lugs forming teeth 14, (see Fig. 4) are provided on the inner face of the boss 12 and a bolt 15 is slidably mounted in the boss 13. This bolt is formed with teeth 16 on 85 its inner end which are adapted to coact with the teeth 14 to tightly engage the sides of the upright when the bolt is projected inwardly. The bolt 15 is formed with a head 17 on its outer end by which the bolt 90 can be withdrawn from or driven into tight engagement with the upright. A spring 18 secured to the boss 13 such as by rivets 19 has its free end pressing down upon a pin 20 on the bolt and serves to releasably hold 95 the bolt tightly engaged with the upright. The horizontal adjacent edges 21 of the sections 6 are made to overlap (see Fig. 4) and the lower edge of the lowermost section is formed with an inwardly projecting lip 22, (see Fig. 1), resting upon the floor of the car, thus producing tight joints which prevent any grain leaking out through the door.

100 In use the I beams are first attached to the vertical beams and floor of the doorway by teeth 11 and 14 and bolt 15 and the sections 6 are superimposed in a vertical plane with their ends engaged in the adjacent channels 105 of the I beams.

In accordance with the patent statutes I have described the principles of operation of my invention together with the apparatus which I now consider to represent the best embodiment thereof, but I desire to have it understood that the construction shown is only illustrative, and that the invention can be carried out by other means and applied to uses other than those above set forth within the scope of the following claims.

Having described my invention, what I claim as new and desire to protect by Letters Patent is:—

1. The combination with a grain car provided with a doorway having uprights at its sides and a floor, of a pair of channel members engaging the inner faces of said uprights, the lower ends of said members being secured to the floor, spaced bosses formed upon either of said members adjacent its upper end and straddling the upright with which it is associated, one of said bosses having teeth upon its inner surface for releasably securing it to a face of the upright, the other of said bosses having a bolt for detachably securing it to a face of the upright, a spring carried by said last mentioned boss tensionally engaging said bolt for retaining it in holding position, and sectional metal closure means for said doorway working in said channel members.

In testimony whereof, I have signed my name to this specification, in the presence of two subscribing witnesses.

CHARLES A. CREAPO.
